UNITED STATES PATENT OFFICE.

WILLIAM MCQUOID, JR., OF GREENOCK, SCOTLAND.

APPARATUS FOR RAISING OR LOWERING SHIPS' BOATS.

SPECIFICATION forming part of Letters Patent No. 623,810, dated April 25, 1899.

Application filed January 9, 1899. Serial No. 701,569. (No model.)

To all whom it may concern:

Be it known that I, WILLIAM MCQUOID, Jr., joiner, a subject of the Queen of Great Britain, residing at 9 Roxburgh street, Greenock, county of Renfrew, Scotland, have invented certain new and useful Improvements in Apparatus for Raising or Lowering Ships' Boats, of which the following is a specification.

This invention relates to improvements in apparatus for raising and lowering ships' boats; and in order that my said invention may be properly understood I have hereunto appended two explanatory sheets of drawings, whereon—

15 Figure 1 is a side elevation of the apparatus. Fig. 2 is a plan of the apparatus. Fig. 3 is a section taken on the line $x-x$, Fig. 2. Figs. 4 and 5 are detail views.

Referring to the drawings, the same reference-letters wherever repeated indicate the same parts.

In carrying out the invention I fit, in connection with each davit a , a winding-drum on which the lowering-falls b can be wound. 25 These drums $c c'$ are mounted upon a shaft d , driven by means of bevel-gearing e from a vertical shaft f with a worm-wheel g thereon, which is operated by a worm h on a cross driving-shaft i , provided with a hand-wheel j or a crank and handle. Fitted in connection with the drum-shaft d is a band-brake k , with operating-screw k' . The band is hinged at k^2 , (see Fig. 4,) and when the screw is operated the said band is forced into frictional contact with the wheel k^3 on the shaft d , so as to brake it. If so desired, an ordinary band-brake and lever may be used.

In order to throw the driving-shaft i into and out of gear whenever necessary, a worm-shaft l is provided, having two worms $l' l''$ on it, which operate two screwed shafts $m m'$, working through the bearing-blocks $o o$ of the driving-shaft. These bearing-blocks are made so as to move backward and forward on guides p , carried by the supports q . If desired, a clutch shifting-gear may be used instead of the worm shifting-gear hereinbefore described.

The davits a can be turned in their sockets so as to throw the boat inboard or outboard 50 by means of the shafts $r r'$, which when operated are caused to turn by means of worms $s s'$ and worm-wheels $t t'$, attached to the davits. The worm-wheels $t t'$ may be made in segments or halves (see Fig. 5) and be bolted to 55 or strapped to the davits, as shown.

The shafts $r r'$ are operated by the bevel-gears $u u$, actuated by the shafts $v v$. Each shaft v , as shown, carries at its upper end a worm-wheel w , which gears with a worm x . 60 Each worm x is carried by a shaft y , and each shaft y is operated by a hand-wheel y' or a crank and handle.

To guide the falls onto the drums, swiveling guide-pulleys z may be used. 65

Each rope or fall b is, as shown, passed over guide-pulleys $b' b' b'$ on each davit to the hook or shackle b^2 at the boat B.

If desired, a single drum may be fitted on the shaft, and upon this drum both ropes b 70 may be wound.

The parts of the apparatus may be arranged in different ways to suit the various types of vessels and the space available for the apparatus. 75

C represents the ship's rail.

Having now fully described my invention, what I claim, and desire to secure by Letters Patent, is—

1. In boat raising and lowering gear the 80 combination of the swiveled davits, the falls, the winding-drum shaft, a bevel-wheel on the shaft gearing with a bevel-wheel on a second shaft, a worm-wheel on said second shaft, a third shaft, a worm on said third shaft gearing with the worm-wheel of the second shaft and means for revolving said third shaft, substantially as set forth.

2. In boat raising and lowering gear the 90 combination of the swiveled davits, the falls, the winding-drum shaft, worm and worm-wheel gear for revolving said shaft, a shaft carried in bearings and operated by hand for actuating the worm-gear, screwed spindles passed through the bearing-blocks of the said 95 bearings and worm-gearing operated by hand

for revolving said screwed spindles substantially as set forth.

3. In boat raising and lowering gear the combination of the davits worm-wheels on 5 said davits shafts with worms thereon gearing with said worm-wheels, bevel-wheels at the ends of said shafts gearing with bevel-wheels on two vertical shafts and worm-gear-

ing operated by hand for revolving said vertical shafts, substantially as set forth. ¹⁰

Signed at Greenock this 17th day of December, 1898.

WM. MCQUOID, JUNR.
